(57) **CLAIM**

The ornamental design for a display screen or portion thereof with an animated graphical user interface for a sustainability simulator, as shown and described.

DESCRIPTION

FIG. 1 is a front view of a display screen or portion thereof with an animated graphical user interface for a sustainability simulator showing a first image according to a first embodiment of our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is a front view of an eleventh image thereof;

FIG. 12 is a front view of a display screen or portion thereof with an animated graphical user interface for a sustainability simulator showing a first image according to a second embodiment of our new design;

FIG. 13 is a front view of a second image thereof;

FIG. 14 is a front view of a third image thereof;

FIG. 15 is a front view of a fourth image thereof;

FIG. 16 is a front view of a fifth image thereof;

FIG. 17 is a front view of a sixth image thereof;

FIG. 18 is a front view of a seventh image thereof;

FIG. 19 is a front view of an eighth image thereof;

FIG. 20 is a front view of a ninth image thereof;

FIG. 21 is a front view of a tenth image thereof; and,

FIG. 22 is a front view of an eleventh image thereof.

The outermost broken lines around the figures show a display screen or portion thereof which form no part of the claimed design. The other broken lines within the figures show portions of the animated graphical user interface that form no part of the claimed design.

The appearance of the animated image sequentially transitions between the images shown in FIGS. 1-11 and 12-22.

(Continued)

The process or period in which one image transitions to another forms no part of the claimed design.
